UNITED STATES PATENT OFFICE.

SAMUEL McCAGHTRY, OF WASHINGTON, PENNSYLVANIA.

GLASS-PRESS.

SPECIFICATION forming part of Letters Patent No. 726,088, dated April 21, 1903.

Application filed April 9, 1902. Serial No. 102,031. (No model.)

To all whom it may concern:

Be it known that I, SAMUEL McCAGHTRY, a citizen of the United States of America, residing at Washington, in the county Washington and State of Pennsylvania, have invented certain new and useful Improvements in Glass-Presses, of which the following is a specification, reference being had therein to the accompanying drawings.

10 This invention relates to certain new and useful improvements in glass-presses, and relates more particularly to ordinary single-plunger presses, in which the table and plunger are capable of being shifted in succession 15 to the position for the work so intended for such mechanism.

The invention has for its object to provide a construction of plunger-actuating mechanism whereby the plunger is actuated for effecting the initial shaping operation; furthermore, to provide novel means whereby the pressure of the plunger is gradually increased as it is lowered.

My invention still further aims to provide means whereby the plunger when it has reached the limit of its downward stroke will be retained for a certain predetermined interval during the final shaping of the glass.

A still further object of my invention is to 30 provide a novel form of yielding connections to the mechanism that will effectually prevent the crushing or straining of the article manufactured.

My invention also contemplates to provide 35 a novel form of mechanism of the above-described character that will be extremely simple in construction, strong, durable, and comparatively inexpensive to manufacture.

With the above and other objects in view 40 the invention consists in the novel construction, combination, and arrangement of parts to be hereinafter more fully described, and specifically pointed out in the claims.

In describing the invention in detail reference is had to the accompanying drawings, forming a part of this specification, and where in like numerals of reference indicate like parts throughout the several views, in which—

Figure 1 is a front view of my improved 45 glass-press. Fig. 2 is a side elevation thereof. Fig. 3 is a detail view of a modified form of

yielding connections. Fig. 4 is a side elevation showing the end of one of the arms.

In the drawings the reference-numeral 1 represents the truck, carrying a table 2, upon which is secured the mold 3. In the truck 1 is mounted a driven shaft 4, carrying a pinion 5, meshing with the cog-wheel 6, which is mounted upon the main shaft 7, extending through the front portion of the truck. This 60 shaft has secured at its ends cams 8, operating against antifriction-rollers 9, which are rotatably secured upon the slotted ends 10 of the arms 11, the upper ends of said arms being pivotally connected at 12 to the cross-head 14, having guideways 15 formed therein, which operate and are slidably connected to the standards 16, which are rigidly secured to the table 2. A cross-head 17 is also slidably mounted upon the standard 16 in like manner. These cross-heads 14 and 17 are provided with central bearings 18 and 19 for the reception of the rod 20, which carries on its lower end the plunger 21, the latter conforming with the interior of the mold 3. The rod 75 20 is screw-threaded near its upper end and carries an adjustable collar 22, and a collar 23 is secured upon the rod 20 below the cross-head 14. Upon the upper face of this collar 23 and encircling the rod 20 is secured a spiral spring 24, said spring being surrounded partially by the heavier coiled spring 25, the latter also resting upon the upper face of the collar 23. In lieu of the springs 24 and 25 one or more springs may be arranged as shown 80 in Fig. 3 of the drawings, two springs operating on the ends and two heavier springs in the center, these springs shown in modified form encircling rods which pass through the cross-head 14. The peculiar arrangement of 85 the springs 24 and 25, or the springs shown in the modified form of Fig. 3 of the drawings, performs a very important function—namely, it gradually increases the pressure of 90 of the plunger upon the article being formed. 95

The operation of my improved press is as follows: The glass is placed in the mold and by the rotation of the shaft 7, to which movement is communicated through the medium of the pinion 5 of the driven shaft 4, the cams 100 8 are operated, and we will assume for the purpose of illustration that the parts are in

the position as shown in Figs. 1 and 2 of the drawings, showing the plunger elevated. As the cams 8 are rotated the lower antifriction-rollers are engaged by the peripheries of the cams 8, thereby drawing downwardly the slotted end 10 of the arm 11, the slotted portion of the arm riding in the shaft 7. By this operation the cross-heads will also be operated downwardly and the gradual pressure of the plunger will be brought to bear upon the glass, which will be increased as the spring 25 is brought under tension or the heavier and shorter springs shown in Fig. 3 of the drawings. Upon reaching the limit of its downward movement the plunger will be raised by the action of the eccentric portions of the cams on the rollers 9.

The many advantages obtained by the use of my improved device will be readily apparent from the foregoing description, taken in connection with the accompanying drawings.

It will be noted that various changes may be made in the details of construction without departing from the general spirit of my invention.

Having fully described my invention, what I claim as new, and desire to secure by Letters Patent, is—

1. In a glass-press, the combination with the table, the standards, and the driven shaft, of a cross-head slidably mounted on the said standards, cams secured on the opposite ends of the said shaft, arms pivotally connected to the said cross-head, and having their lower ends formed with elongated slots, through which the ends of the said shaft extend rollers secured to the said arms on opposite sides of each of the said cams, a rod mounted in the said cross-head, a collar secured to the said rod, and springs of varying strength secured to the said collar, one of which is engaged by the cross-head as the same is moved downwardly.

2. In a glass-press, the combination with the supporting-standards, of a cross-head slidably mounted on the said standards, a rod mounted in the said cross-head, a collar secured to the said rod beneath the said cross-head, and springs secured to the said collar, one of which has its upper end normally in engagement with the said cross-head, and another being engaged by the cross-head on its downward movement.

3. In a glass-press, the combination with the table and supporting-standards, of a cross-head slidably mounted on said standards, a rod mounted in said cross-head, a plunger, a collar secured to the said rod below the cross-head, springs of varying strength secured to the said collar, certain of which have their upper ends normally in engagement with the said cross-head, the others being engaged as the cross-head is lowered, and means to impart an intermittent reciprocating movement to the said rod, substantially as described.

4. In a glass-press, the combination with the table and supporting-standards, of a cross-head slidably mounted on said standards, a plunger-rod loosely mounted in said cross-head and having its upper end screw-threaded, an adjustable collar secured on the said screw-threaded end, a collar secured to the said plunger-rod at a point below the said cross-head, springs of varying strength encircling the said plunger-rod and secured to the last-named collar, and adapted to be engaged by the said cross-head, and means to impart a reciprocating movement to said plunger.

In testimony whereof I affix my signature in the presence of two witnesses.

SAMUEL McCAGHTRY.
